COOKING STOVE

John R. Morgan, Chicago, and Melvin H. Boldt,
Glenview, Ill., assignors to Crown Stove Works,
Chicago, Ill., a corporation of Illinois

Application January 5, 1951, Serial No. 13,682

Term of patent 14 years

(Cl. D81—4)

To all whom it may concern:

Be it known that we, John R. Morgan, a citizen of the United States, residing at Chicago, in the county of Cook and State of Illinois; and Melvin H. Boldt, a citizen of the United States, residing at Glenview, in the county of Cook and State of Illinois; have invented a new, original, and ornamental Design for a Cooking Stove, of which the following is a specification, reference being had to the accompanying drawing, forming part thereof:

Figure 1 is a perspective view of a cooking stove embodying our new design, and

Figure 2 is an end elevation thereof taken from the right of Figure 1.

The side not shown is like the side shown.

We claim:

The ornamental design for a cooking stove, substantially as shown and described.

JOHN R. MORGAN.
MELVIN H. BOLDT.
